United States Patent Office

Des. 175,304
Patented Aug. 9, 1955

175,304

MEAT LIFTER

Charlotte P. Gorin, Seattle, Wash., assignor to Foley Manufacturing Company, Minneapolis, Minn., a corporation of Minnesota

Application December 29, 1954, Serial No. 33,730

Term of patent 14 years

(Cl. D44—29)

FIG. 1

FIG. 2

Figure 1 is a perspective view of a meat lifter showing my new design; and

Figure 2 is a side elevational view thereof.

I claim:

The ornamental design for a meat lifter, as shown.
